UNITED STATES PATENT OFFICE.

STEPHEN H. FARNHAM, OF BROOKLYN, NEW YORK, ASSIGNOR TO REMINGTON TYPE-WRITER COMPANY, OF ILION, NEW YORK, A CORPORATION OF NEW YORK.

ACCOUNTING-SHEET.

1,250,443.

Specification of Letters Patent. Patented Dec. 18, 1917.

Application filed August 4, 1916. Serial No. 113,102.

To all whom it may concern:

Be it known that I, STEPHEN H. FARNHAM, citizen of the United States, and resident of the borough of Brooklyn, city of New York, in the county of Kings and State of New York, have invented certain new and useful Improvements in Accounting-Sheets, of which the following is a specification.

10 My present invention relates to means whereby manifolding or duplicating may be facilitated, and especially to means for facilitating duplicating in commercial accounting work whereby the work sheets may be 15 relatively adjusted and re-adjusted and maintained securely in the proper relationship after such relative adjustment. The means by which this is accomplished is self-contained, or in other words, the sheets 20 themselves, or devices carried by them, are made to perform the desired functions without employing any extraneous means or devices, as has heretofore been necessary. Stated in another way, the sheets are made 25 to interlock, preferably by causing tongues formed along the edge of or carried by one sheet or sheets to engage with corresponding perforations on another sheet or sheets, although the interlocking means is not necessarily confined to such a construction.

To the above and other ends my present invention consists in the features of construction, combinations of devices and arrangements of parts hereinafter described 35 and particularly pointed out in the claims.

The principles and use of my invention will be more fully explained and described in connection with the accompanying drawings, wherein—

40 Figure 1 is a face view showing the inner face of a work sheet or bill sheet hereinafter referred to as a "monthly statement sheet."

Fig. 2 is a face view of a work sheet hereinafter referred to as a "ledger sheet."

45 Fig. 3 is an enlarged cross sectional view showing the statement sheet and ledger sheet interlocked or mutually engaged, together with an interposed carbon sheet.

Fig. 4 is a perspective view showing the 50 statement sheet, ledger sheet and carbon sheet interleaved and properly adjusted.

Fig. 5 is a face view of a modification of the ledger sheet.

Referring generally to the work sheets 55 illustrated, the ledger sheet 1, which is suit-

ably printed in blank, as illustrated in Fig. 2, has entered on it from day to day the various purchases of a customer, whose name is entered in the blank space opposite "Name," and to whose account alone the ledger sheet 60 is devoted. This ledger sheet may cover a period of time extending over several months or even longer. The monthly statement sheet, 2, on the other hand, the back of which is shown in Fig. 1, and the front 65 partly illustrated in Fig. 4, covers the customer's account for only a single month, at the end of which time it is sent out to the customer. All items on the monthly statement sheet 2 are repeated or duplicated on 70 the ledger sheet 1, which ledger sheet may contain the entries of several monthly statement sheets, these entries being preferably written in duplicate on the ledger sheet, when the statement sheet is written, through 75 an interposed carbon sheet 3, although the ledger sheet in some instances may be written direct from the ribbon of the typewriter. It will be understood that it is necessary to keep the ledger and monthly statement 80 sheets in the same relationship, after they have once been started, to the end of the month, and also that after the first statement sheet is finished and a new monthly statement sheet is begun this second monthly 85 statement sheet must be so adjusted in respect to the ledger sheet that the entries on the ledger duplicated from the second monthly statement sheet will follow directly under the ledger entries for the preceding 90 month. For example, referring to the entries on the illustrated sheets, it is necessary or desirable that the August entries on the record or ledger sheet follow directly under the July entries without any waste space 95 between them and also without any possibility of encroaching with the first line of the August statement on any of the preceding entries.

With the object in mind of facilitating the 100 carrying out of these desiderata, I preferably provide one of the work sheets with a series of holes or perforations, and the other work sheet with a corresponding series of projections or teeth to interseat with said 105 holes and thus effect an interlocking engagement between the work sheets. In the present instance, the statement sheet 2, which may of course be a multiple fold sheet, is shown as comprising two parts, the sheet 110

proper 4, (the front face of which receives entries), and a narrow flap 5, which is joined to the main portion 4 by a fold or crease 6. The fold 6, which may be at either side in the present instance, is shown at the left-hand side edge of the sheet 4, when in working position, and the flap 5 is folded behind the left-hand marginal portion of the sheet 4. The series of holes or perforations 7 is formed lengthwise of the fold or crease 6 and so that substantially half of each hole is in the sheet portion 4 and half in the flap 5. In the present instance these holes 7 are preferably a unit of line space distance apart, having reference to the line spacing of a typewriting machine, since the typewriting, as illustrated in the drawings, is printed "single space." But, of course, it is to be understood that the distance apart of the holes may be varied as found desirable, and they may be two, or three, or more, units of line space distance apart or even less than a unit of line space distance. In the specimen sheet shown the series of holes 25 extend from the bottom to the top of the sheet and afford means for facilitating the detachment of the flap 5 when the sheet is completed. In some styles of work, instead of the narrow flap 5, a wider portion may be preferable, in some cases this portion being of a width equal to that of the front portion 4, or in some instances wider, for binding space or other purpose. As will be best understood from Fig. 4, the upper portion 30 of the front face of the sheet proper 4 is devoted to the heading, which contains the style of the firm or concern and other necessary or advertising matter. In the drawing, however, the sheet is turned down somewhat so that the heading space is not fully illustrated. Below the heading the sheet 4 is ruled into columns for the date of the transaction, description of the goods, debits, credits, balance, etc. In a single-charge-per-day system, such as is herein illustrated, a single line only is devoted to the entire transactions of a single day. The left-hand column is numbered to correspond with said single lines 1, 2, 3, etc., down through 31, each number being opposite one of the holes 7. Inside the sheet proper 4, opposite the holes, there is a duplicate set of numbers from 1 to 31 as shown at Fig. 1. In other words, each hole 7 below the heading has its number close to it at one side on both the front and back of the sheet proper 4.

The ledger sheet 1 is printed in blank on both its front and rear sides to correspond with the printing on the front of the sheet proper 4. Along its left-hand side edge the ledger sheet 1, which usually is of somewhat stiff paper, is formed or provided with a set of lateral projections, tongues or teeth 8 which are shaped to fit into the holes 7 and are spaced apart correspondingly to the

spacing of the holes. Similarly the right-hand side edge of the ledger sheet 1 is formed or provided with teeth 8 of the same sort, so that when one side of the ledger sheet is completely filled the sheet may be turned over and the opposite side filled. After the ledger sheet is full on both sides it may be permanently filed away in a book, holes 9 near its lower edge facilitating the filing operation. The left-hand column on the ledger sheet is numbered in correspondence with the numbering in the left-hand column and on the back or rear face of the sheet proper 4, but, of course, the numbers on the ledger sheet are arranged opposite the projections or teeth 8.

While I have shown the line numbers printed in full on the ledger sheet and have "skeletonized" them after 10, 20 and 30 on the statement sheet, this variation in notation is of course immaterial. They may be both printed alike or as shown, or other indicia may be employed.

In making use of the sheets they are first properly adjusted relatively to each other by arranging the ledger sheet 1 with its left-hand edge in the fold 6 of the statement sheet and with the tooth numbered 1 engaging with hole or slot numbered 1, tooth at 2 engaging with hole numbered 2, and so on, it being understood that when the desired tooth has been registered with the desired perforation all of the remaining teeth will register, and by pushing the teeth through the perforations the two sheets become completely interlocked and held against accidental movement lengthwise of each other, so that their relationship cannot be altered except through design. When next the carbon sheet 3 has been inserted between the sheet proper 4 and the ledger sheet 1, the sheets are ready to be written upon. First, the blanks in the heading are filled in, viz.—the "Account No.", the "Sheet No." and the "Name". Next, the entry opposite line 1 is filled in, this entry in the illustrative sheet shown in Fig. 2 comprising these quoted items, viz.—"1" (i. e., the day of the month); "Mdse"; "1" (folio); "100 00" (debit); "100 00" (balance).

It will be understood that all the entries are written on the front face of sheet 4 through the usual ribbon of the typewriting machine, or otherwise if preferred and duplicated simultaneously on the ledger sheet 1 through the interposed carbon sheet 3. After the entry of the first line is completed the sheets are removed from the typewriting machine to make way for other work and are filed in a convenient place or binder until the next transaction with the customer, during that month, takes place. In the present instance it will be observed that transactions took place on the 2nd, 3rd, 15th and 23rd of the month of July, thereby resulting in

filling in five lines on both the monthly statement sheet and the ledger sheet. It will be understood that the relationship between the two sheets 1 and 2 remains unchanged 5 throughout the month, so that at the end of the month when the statement sheet is mailed to the customer with its said five lines of data of transactions, the ledger sheet which is retained in the office will contain 10 an exact duplicate of such data. The statement sheet having been mailed the ledger sheet is next adjusted in the fold of a new statement sheet for the following month "August", the proper adjustment being both 15 obtained in the first place and thereafter maintained by reason of my invention. Thus since the sixth line is the next line to be written on the ledger sheet, as indicated by the numeral in the first or left-hand column, the sixth tooth (said tooth being indicated by the reference character 8' for the sake of clearness) is inserted in the hole above the "1" hole in the new statement sheet, the flap 5 being turned back to facilitate such insertion; after which the two 20 folds or plies 4 and 5 of the new sheet 2 are folded around the ledger sheet, the teeth 8 being pressed into engagement with the holes 7, and the carbon paper inserted. The 25 ledger sheet and the new statement sheet will now be in the relationship illustrated in Fig. 4, from which it will be understood that when the word "August" is printed at the head of the date column on the new statement sheet it will, through the carbon, be 30 duplicated as shown in Fig. 2, on line sixth of the day column on the ledger sheet. The first line in the new August statement sheet will be duplicated in line seventh of the 35 ledger sheet, and so on until all of the August transactions have been written, after which the August statement sheet is to be sent out and thereafter substituted by a September statement sheet, the entries whereof 40 may be duplicated on the ledger sheet under the August entries and in proper relationship thereto after the ledger sheet has been interlocked with the statement sheet in the manner heretofore described, the relative adjustment 45 between the two being effected as has been explained. It should be said that all data in the headings of statement sheets subsequent to the first sheet are filled in before the ledger sheet and statement sheet are 50 put together.

Many variations in the means of carrying out the principles of my present invention will readily suggest themselves to those skilled in the art. For example, the side 55 edges of the ledger sheet instead of being provided with continuous series of teeth along its side edges may have only a few teeth at intervals near its top and bottom and perhaps at about midway of its length. 60 In Fig. 5 is shown a modified ledger sheet

10 having such characteristics. The sheet 10 is provided at each side edge with two teeth 11 near the top and two teeth 11 near the bottom. There are also shown two teeth 12 at about the middle; these teeth 12, as shown, 70 as well as others, instead of being integral with the sheet 10 may be made separate and applied to the sheet in any suitable way as by an adhesive or by being clipped or clasped to the sheet. Similarly the holes in the 75 statement sheet may be formed in a separate slip which may be gummed on or otherwise applied to the sheet proper. Also instead of being formed with holes the statement sheet may have pockets or depressions or 80 similar devices with which portions of the ledger sheet may cooperate to interlock the two sheets. The detachable form of interlocking devices may be preferred where, for example, the ledger sheet is of thin material 85 and the projections as 12 may be of heavier material. Also, if the interlocking devices are detachable from the sheets so that they may be removed after the sheets are completed, the possible objection to rough or 90 serrated edges is avoided. Various other changes besides those referred to will fall within my present invention.

It will be observed that by my invention 95 there are provided, in combination with two separate work sheets, means carried by said sheets for variably fixing the relationship between said sheets, the variations in such relationship corresponding preferably with the line spacing distances through which 100 the sheets would be advanced step-by-step when fed through a typewriting machine, although of course such specific variation is not essential; that the means for variably fixing the relationship comprises preferably 105 a set of devices or projections on one sheet that are adapted to engage receiving means in the other; that said receiving means preferably comprise a set of devices or series of holes or perforations; that two separate 110 work sheets are combined with self-contained means for effecting interlocking engagement of said sheets; that means for interlocking two sheets are provided which are carried wholly by the sheets; that interlocking means for two separate work sheets are provided, which means may be integral with the two sheets; that a work sheet is provided having an edge portion adapted to the fold or crease of another sheet which 115 has two folds or plies, the folded sheet being perforated along the fold or crease and the perforations receiving teeth or projections along the edge portion of the other sheet; that the projections and the perforations 120 provide interlocking means by which relative displacement of the two sheets lengthwise of the fold is prevented; that the sheet with the projections preferably has two sets of projections at opposite edges so that 125 130

such sheet may be turned over and written on both sides, the interlocking engagement with the folded sheet being maintainable during the writing of both sides; that the 5 means carried by the sheets for variably fixing their relationship are partly carried by one of said sheets and partly by the other; that suitable indicating marks or other indicia are associated with the means and the 10 parts of the means so as to facilitate the bringing together in desired relationship of the parts of the means and the sheets by which they are carried; and that the indicia in the present instance consist of numbers 15 opposite the teeth on the ledger sheet and corresponding numbers opposite the holes on both the front and back of the statement sheet.

Of course, in a business where it is common to have a considerable number of transactions with a customer in the course of a day, the system of accounting is preferably varied accordingly and each line on a statement sheet may be devoted to a transaction 20 so that one day may occupy a considerable number of lines on the statement sheet as well as on the ledger sheet. However, it will be apparent that my invention will take care of this, as the indicating marks 25 opposite the holes on the statement sheet and the teeth on the ledger sheet may always be employed properly to register the ledger sheet with the statement sheet.

What I claim as new and desire to secure 30 by Letters Patent, is:—

1. The combination with two separate work sheets, of self-contained means for effecting interlocking engagement of said sheets at predetermined points, the points 40 being variable at will.

2. The combination with two separate work sheets, of means for interlocking the two sheets at predetermined points, the points being variable at will, said means being carried by the sheets. 45

3. The combination with two separate work sheets, of means integral with the two sheets for interlocking them, said means comprising two sets of devices, one set on 50 one sheet, and one on the other, said two sets of devices being engageable separably and reengageable in a different relationship from the first engagement without affecting the devices in themselves.

4. The combination with a folded work sheet and a second work sheet having an edge portion adapted to the fold of the first sheet, of interlocking means for preventing relative displacement of the two sheets 60 lengthwise of said fold, said interlocking means being carried wholly by the two sheets and comprising two sets of co-acting devices, one set on one sheet, and one set on the other, the two sets being variably 65 engageable at will.

5. The combination with a folded work sheet and a second work sheet having an edge portion adapted to the fold of the first sheet, of interlocking means for preventing relative displacement of the two sheets 70 lengthwise of said fold, said interlocking means comprising projections on one sheet which are adapted to variably engage receiving means in the other sheet.

6. The combination of a folded work 75 sheet, and a second work sheet having an edge portion adapted to the fold of the first sheet, said fold being provided with a series of perforations and said edge portions having projections engageable variably with 80 said perforations to interlock the two sheets in different relationships.

7. The combination of two interlocking work sheets, one provided with projections adapted to variably engage receiving means 85 in the other.

8. The combination of a work sheet provided with a series of holes and a second sheet provided with projections adapted to variably engage in said holes. 90

9. The combination of a folded work sheet provided with a plurality of holes along said fold and a second work sheet provided at opposite edges with projections for variable engagement with said holes. 95

10. The combination with two separate work sheets, of means carried by said sheets for variably fixing said sheets in predetermined relationships.

11. The combination with two separate 100 work sheets, of means carried by said sheets for variably fixing the relationship between said sheets, the variations in the relationship corresponding with the units of line space distance that the sheets may be advanced step by step in a typewriting machine. 105

12. The combination of a work sheet provided with a series of holes and a second sheet provided with projections adapted to 110 variably engage in said holes, said holes being spaced apart to correspond with the line spacing of a typewriting machine.

13. The combination of a folded work sheet provided with a series of holes along 115 its fold, a second work sheet provided with projections along one edge adapted to variably engage in said holes, and a carbon or transfer sheet interposed between the two work sheets.

14. The combination of two separate work sheets, of means carried in part by one sheet and in part by the other for variably fixing the relationship between said sheets from time to time in accordance with the 125 requirements for readjustment.

15. The combination with a folded work sheet and a second work sheet having an edge portion adapted to the fold of the first sheet, of interlocking means for prevent- 130

ing relative displacement of the two sheets lengthwise of said fold, said interlocking means comprising projections on one sheet which are adapted to engage receiving means in the other sheet, one sheet having indicating marks associated with the projections and the holes being correspondingly indicated both on the front and the back of the sheet containing them.

10 16. The combination of a work sheet provided with a series of holes and a second sheet provided with projections adapted to variably engage in said holes, the projections being provided with indicating marks and corresponding indicating marks being placed opposite the holes.

15 17. The combination of a folded work sheet provided with a plurality of holes along said fold and a second work sheet provided with projections for engagement with said holes, the projections being suitably in-

dicated, and the folded sheet being correspondingly provided with indicating marks on both front and back opposite the holes.

18. The combination of two separate 25 work sheets, of means carried in part by one sheet and in part by the other for variably fixing the relationship between said sheets from time to time in accordance with the requirements for readjustment, suitable indicia being provided in connection with said means so as to facilitate the bringing of the parts into desired relationships.

Signed at the borough of Manhattan, city of New York, in the county of New York 30 and State of New York, this 3 day of August, A. D. 1916.
